HOLDER FOR NOTES

Orson Warren Lake, 289 N. Greece Road, Hilton, N.Y.

Filed Nov. 13, 1962, Ser. No. 72,454

Term of patent 14 years

(Cl. D17—3)

Fig. 1

Fig. 3

FIG. 1 is a top plan view of a holder for notes embodying my new design with a telephone being shown in broken lines for illustrative purpose only;

FIG. 2 is an enlarged front elevational view; and

FIG. 3 is an enlarged side elevational view thereof.

The back of the article is substantially plain and unornamented.

I claim:

The ornamental design for a holder for notes, substantially as shown and described.
